Baronets Langdon and William Murray.

Letters Patent.

The schedule referred to in these Letters Patent and making part of the same containing a description in the words of the said Baronets Langdon and William Murray themselves of their Machine, for shaving, jointing, and forming the staves and heads of barrels &c.

This Machine consists of the following parts viz. the machinery for shaving and dressing the staves; - the machinery for jointing; - and the machinery for dressing, dovelling and cutting the heading -

The machinery for dressing staves, is composed of two plane stocks standing vertically, with any number of plane-irons either double or single, the irons on one side covering the outer side of the staves, and the irons on the other side following it agreeably to the size of the staves or barrel to be formed. The rough staves being placed on its edge on a sliding carriage which traverses by means of a toothed rack & pinion between, or by means of a single rack or slide carried back by a weight in, by the operation of these plane irons, dressed into its proper form and thickness by one operation, or once passing between the stocks. The stocks in which the plane irons are placed, may be made of metal, or other sufficiently strong material; and the plane irons are fixed and adjusted in them by screws descending from the upper surface upon their edges.

The machinery for jointing is placed in the same line with the former, so that a carriage moved by the same rack and pinion may answer, or if circumstances render it more convenient, a separate rack and pinion, and carriage may be used, at the option of the constructor.

Perpendicularly over the rack, and attached thereto, is the carriage for receiving and holding the staves to be jointed. The carriage stands vertically, and has a moveable upper jaw extending its whole length between which, and a fixed horizontal under jaw the staves is laid with the concave side downwards, it is held in the position by a wedge, screw or lever. On the upper part of the carriage are gages formed corresponding to the inner or edge.

of the stone, so that as the carriage is passed along with the stone it may be
easily taken the stone along and out as the carriage takes it on
other side. This is effected by placing iron on each side standing upright,
but adjusted by screws to such inclination as shall give the proper
to the edge of the stone, according to the diameter of the barrel or such
being fixed and adjusted by screws and supported on sliding beds, which oppo-
site, each other, as the operation is performing. These joints, and the hori-
zontal rock, are moved by balanced forces guided by gauges in which the stone
placed, and particularly described above.

After the stone has passed through
between the jointing irons one way, the beds and iron connected therewith
then reducing the stone are thrown back by a spring, and as the carriage & stone
action again the contrary direction: the joints are released, and another
commences their operation, so as to joint and taper the other end of the stone in
true manner.

The beds of the sliding carriage, which support the joint
may be regulated by screws, to the width of certain descriptions of stones, as
the stones desired accordingly: so they may be so fixed that when the stone is put
in the carriage, its width shall operate on levers connected with the beds of the
jointing, so as to move them to suit the width of the stone, and stones of any
width may be admitted indiscriminately without previous ascertainment.

As the rock and piston by which these carriages are moved are of a few
kinds construction it will be necessary to particularly to describe them.

There are two parallel rocks of rock in the same form and facing each
other, connected at their ends by similar teeth in form of a circle & con-
founding with the teeth of the piston, so that the two rocks and their con-
necting ends form a long parallelogram with teeth in straight rows above
and below and in portions of a circle at the ends. After the piston has been a-
eing on the lower rock or side of the parallelogram and making the end of
the rock, the teeth of the piston begin to act on teeth in the portion of a
circle, connecting the two rocks by which means the piston is raised to move
in the teeth of the upper horizontal rock, and the axis of the piston is
at that elevation by a spring and catch or peg, which locks into a short
bar that supports the axis of the piston. The revolution of the piston
by its teeth meshing with those of the upper rock, give the rock a con-
stant

motion to the spur wheel, when a pin turns the end of a spur wheel, and by the teeth on the side of the parallelogram the pinion moves to the lower knot, and is forced again by a slot or peg in the front portion. Thus by an unceasingly revolving motion of the pinion the sack moves alternately, each way & bears the carriage with the flax accordingly.

A spur wheel connected with the sack above described, belongs to a sliding knife frame which moves horizontally in a box wide enough to contain the heading stuff. This is laid flat on a rising bench within the box so that when the heading is placed on the bench it can be raised at pleasure and the sliding knife, passing over it, will shear off drops of stuff at the required thickness. These drops may be placed with any degree of regularity, and although it is mentioned that this is moved by the racks before described yet it may be a separate machine or connected with any other of its movements and worked separately. The same machinery by adding guides to raise the bench and by substituting the proper planes, will serve to plane ship for bats, splits for boxes, & other purposes and we hereby describe it accordingly.

On the inner end of the axis of the pinion which moves the sack is a spur wheel, the teeth of which turns a roller spur wheel pinion or mandrel head on a horizontal mandrel, having at its end a flat clamp nearly of the size of the head to be cut, and against which the head is placed to be cut to the proper size. In the same line with this mandrel is a screw mandrel or follower with a similar flat clamp, so that the heading is firmly held between them and resting with the mandrel, on this horizontal mandrel is an earthen screw which gives motion to a horizontal wheel, that has on its axis a drill, ram or lower wheel, that rolls horizontal wheel scalding, advances the cutters together, and the head is cut out truly circular and with the proper level edge. These cutters are placed opposite to each other and are kept together by springs except when forced together by the small screw mentioned.

On this horizontal mandrel is a whorl or spur wheel which gives motion to the downing bits, by a band or otherwise. Another wheel or whorl placed in the extremity of the pinion axis communicates motion to the shaft of a large wheel which with four broad bands, planes or hatchet,
